APPARATUS FOR CONCENTRATING MINERALS BY FLOTATION.

1,156,041.

Specification of Letters Patent.

Patented Oct. 5, 1915.

Application filed November 16, 1914. Serial No. 872,353.

To all whom it may concern:

Be it known that I, GEORGE C. STONE, a citizen of the United States, residing in the city, county, and State of New York, have 5 invented certain new and useful Improvements in Apparatus for Concentrating Minerals by Flotation; and I do hereby declare the following to be a full, clear, and exact description of the invention, such as will 10 enable others skilled in the art to which it appertains to make and use the same.

This invention relates to apparatus for use in the separation of flotable minerals from material with which they are associated. The material to be separated, as for instance, zinc blende, associated with calcite or the like, is first ground or crushed to say from 14 to 16 mesh and is then mixed with the customary flotation emulsion of sulfuric 20 acid, oil and water, prior to flotation. The effect of the sulfuric acid is apparently to clean the oxid from the surface of the sulfid particles, and the oil thereupon envelops the cleaned particles, thus rendering them more 25 susceptible to flotation. Calcite, silica, and the like, will not receive an oil film and are not subject to flotation thereby.

The present invention involves the introduction of the ore into the flotation liquid 30 intermittently, preferably in relatively small individual charges, and the provision of apparatus whereby this may be effected with a negligible amount of agitation of the liquid. To this end a carrier is provided for 35 introducing the ore into the flotation liquid from a source exterior to the receptacle for that liquid, and this carrier is made to enter the flotation liquid by movement in substantially the plane in which it lies. Preferably, 40 the carrier is made up of a series of individual units movable in unison and which move into and out of the flotation liquid at an acute angle to the surface of the flotation liquid.

45 I prefer to employ a carrier provided with a series of trough-like pans open at their forward ends, and to move this carrier into and out of the flotation liquid by a reciprocating movement. When such a carrier is 50 employed in conjunction with mechanism for reciprocating it at an incline so as to project the trough-like pans into the flotation liquid and then to withdraw them therefrom, the checking of the downward

movement of the carrier will result in a 55 continuation of the movement by the ore and its discharge from the carrier into the liquid. When the carrier moves upwardly out of the flotation liquid it may be brought into coaction with a suitable source of supply of ore, and if desired, such source of supply may be provided with a gate controlling the outlet therefrom, which gate is automatically actuated by the movement of the carrier so that the carrier will at once 60 receive a new charge of ore preparatory to a repetition of the downward movement into the flotation liquid.

I have illustrated the preferred embodiment of my invention in the accompanying 70 drawings, in which—

Figure 1 is an elevation of the apparatus employed, the receptacle for the flotation liquid being shown in section and the operating mechanism for reciprocating the carrier being shown diagrammatically; Fig. 2 is a view similar to Fig. 1, showing the carrier in a different position; and Fig. 3 is a transverse section on line 3—3 of Fig. 1.

Referring to these drawings, a receptacle 80 4 is provided for the flotation liquid, this receptacle being of any suitable form.

Extending along one side of the receptacle 4 is the launder 5 into which the overflow from the receptacle 4, with the mineral particles floated thereon, may be discharged 85 over the barrier 6. The supply of the flotation liquid to the receptacle 4 is constantly maintained through the supply pipe 7, and the overflow entering the launder 5 90 is drawn off through the conduit 8. Both the receptacle 4 and the launder 5 are preferably provided with drain openings through which they may be emptied and cleaned, these openings being provided with 95 suitable water-tight gates 9.

Above the receptacle 4 are rails 10, preferably shaped as shown, with the lower portion thereof inclined to the horizontal and with short horizontal extensions at the upper 100 ends of these inclined portions. These rails 10 receive a traveling truck 11 provided with wheels 12 running on the rails 10. Bars 13, and hanger rods 14 supporting the yoke 24, depend from the truck 11 and form 105 a suspending means for a plurality of carriers 15 for the ore to be separated. These carriers are preferably in the form of long

5 relatively narrow troughs open at their forward ends, and mounted at their rear ends upon the through rod 25 so as to have a capacity for being rocked thereon to the 10 particular inclination desired.

15 A substantial number of the troughs 15 is employed, arranged parallel to each other and spaced at convenient distances apart. The hanger rods 14 are screw-threaded at 20 their upper ends and are provided with co-operating nuts, so as to set the troughs at the desired angle.

25 Any suitable means may be provided for reciprocating the wheeled truck or support 11 and the carriers 15 depending therefrom. In the present instance, I have shown a power shaft 16 having a crank arm 17 thereon whose connecting rod 18 engages the front axle of the wheeled support 11, so 30 that rotation of the power shaft 16 causes reciprocation of the support 11 and troughs 15 from the position in which they are shown in Fig. 1 to the position in which they are shown in Fig. 2 and vice versa.

35 When the carriers 15 move to the position in which they are shown in Fig. 1, they may be arranged to co-act with a source of supply of appropriately crushed ore so that each of the several carriers will receive a 40 charge of ore. In the present instance, the source of supply of ore is shown as provided with a plurality of narrow chutes 19, one for each of the troughs 15, down which the ore will pass from a bin. A gate 20 is 45 provided for closing the lower ends of these chutes 19. This gate may be arranged for automatic actuation by the wheeled support 11, or a part mounted thereon, so that as the carriers 15 reach the Fig. 1 position, the 50 gate 20 will be automatically raised to permit the flow of a suitable quantity of ore from each of the chutes 19 into the corresponding carrier 15. For this purpose the gate 20 is shown as pivotally mounted and 55 provided with a crank arm 21 on which is an adjustable stop 22 adapted to be engaged by an abutment 23 upon one of the angle bars 13. Thus, on movement of the carriers 15 to the upper position, as shown in Fig. 1, the gate 20 will be raised and the carriers 60 will receive charges of ore to be treated.

65 It will be noted that the construction herein shown and described is such that the several carriers 15 in moving from the position shown in Fig. 1 to the position shown in Fig. 2 will enter the flotation liquid in the receptacle 4 by movement of the carriers in substantially the plane in which they lie. 70 Movement of the carriers in this way is effected by the bend given to the rails 10, and it results in immersing the carriers and the charges of ore contained in them in the flotation liquid with a minimum of agitation of the flotation liquid, and at an acute angle to the 75 surface of the liquid. In the present in-

stance, where the movement of the carriers is a reciprocatory one, the cessation of the downward movement of the carriers in conjunction with the angle of inclination thereof, is sufficient to effect the discharge of the 80 ore from the open lower ends of the carriers. The carriers are then withdrawn from the liquid on their reverse upward movement, and the ore which has been discharged into the liquid in a plurality of small streams 85 which are spaced apart, is acted upon by the liquid in accordance with the principles of mineral separation by flotation. The values contained in the ore rise to the surface of the liquid and are floated over the barrier 90 6 into the launder 5, from which they are withdrawn by the conduit 8. When the carriers in their upward movement reach the position shown by Fig. 1, the gate 20 is raised by the coacting parts 23 and 22 so 95 that each of the several carriers 15 receives a new supply of ore from the corresponding chute 19.

I claim:—

1. Apparatus for the separation of floatable minerals from materials with which they are associated, comprising a receptacle for the flotation liquid, a carrier for the charge to be separated, and power-actuated devices for reciprocating the carrier over a 100 prescribed path from a point exterior to the receptacle into the latter so as to immerse the charge in the liquid therein; substantially as described.

2. Apparatus for the separation of floatable minerals from materials with which they are associated, comprising a receptacle for the flotation liquid, a carrier for the charge to be separated, power-actuated devices for reciprocating the carrier over a 105 prescribed path from a point exterior to the receptacle into the latter so as to immerse the charge in the liquid therein, and means for supplying a charge of the material to the carrier when the latter is outside the receptacle; substantially as described.

3. Apparatus for the separation of floatable minerals from materials with which they are associated, comprising a receptacle for the flotation liquid, a carrier for the charge to be separated, power-actuated devices for reciprocating the carrier over a 110 prescribed path from a point exterior to the receptacle into the latter so as to immerse the charge in the liquid therein, and means for supplying a charge of the material to the carrier when the latter is outside the receptacle, the carrier being so constructed as to discharge the material therein into the liquid in the receptacle at the termination of 115 movement of the carrier into the liquid in the receptacle; substantially as described.

4. Apparatus for the separation of floatable minerals from materials with which they are associated, comprising a receptacle 120

- for the flotation liquid, a carrier for the charge to be separated, power-actuated devices for reciprocating the carrier over a prescribed path from a point exterior to the receptacle into the latter so as to immerse the charge in the liquid therein, a source of supply of the charge to be separated outside of the receptacle, and automatically operated devices for supplying a charge from the source of supply to the carrier when the latter is outside of the receptacle, substantially as described.

5. Apparatus for the separation of floatable minerals from materials with which they are associated, comprising a receptacle for the flotation liquid, a carrier for the charge to be separated, and means for moving the carrier wholly into and retracting it wholly from the flotation liquid in a substantially rectilinear path and in a direction inclined to the horizontal; substantially as described.

10. 6. Apparatus for the separation of floatable minerals from materials with which they are associated, comprising a receptacle for the flotation liquid, a source of supply of the charge to be separated, a trough-like carrier out of the liquid, and means for intermittently moving the carrier into coaction with said source of supply and then wholly into the liquid in the receptacle in a direction inclined to the horizontal; substantially as described.

15. 7. Apparatus for the separation of floatable minerals from materials with which they are associated, comprising a receptacle for the flotation liquid, a source of supply of the charge to be separated outside of and spaced from the receptacle, a trough-like carrier, and means for intermittently moving the carrier into coaction with said source of supply and then in a substantially rectilinear path into the liquid in the receptacle; substantially as described.

20. 8. Apparatus for the separation of floatable minerals from materials with which they are associated, comprising a receptacle for the flotation liquid, a source of supply of the charge to be separated outside of and spaced from the receptacle, a carrier for the charge to be separated, power-actuated devices for reciprocating the carrier over a prescribed path from a point exterior to the receptacle into the latter so as to immerse the charge in the liquid therein, a source of supply of the charge to be separated outside of and spaced from the receptacle, and automatically operated devices for supplying a charge from the source of supply to the carrier when the latter is outside of the receptacle, substantially as described.

25. 9. Apparatus for the separation of floatable minerals from materials with which they are associated, comprising a receptacle for the flotation liquid, a source of supply of the charge to be separated outside of and spaced from the receptacle, a carrier, means for moving the carrier alternately into coaction with said source of supply and into the liquid in the receptacle, and means actuated by the movement of the carrier for causing automatic delivery of the charge from said source into the carrier; substantially as described.

30. 10. Apparatus for the separation of floatable minerals from materials with which they are associated, comprising a receptacle for the flotation liquid, a source of supply of the charge to be separated outside of and spaced from the receptacle, a gate controlling the exit from the source of supply, a carrier, means for reciprocating the carrier in a path inclined to the horizontal to immerse the carrier in the liquid in said receptacle and to move it into coaction with said source of supply, and means actuated by the movement of the carrier for actuating said gate; substantially as described.

35. 11. Apparatus for the separation of floatable minerals from materials with which they are associated, comprising a receptacle for the flotation liquid, a source of supply of the charge to be separated outside of and spaced from the receptacle, a plurality of carrier troughs arranged parallel to each other and spaced apart, means for supplying ore to the several carrier troughs from said source and means for moving the carrier troughs endwise into the liquid; substantially as described.

40. 12. Apparatus for the separation of floatable minerals from materials with which they are associated, comprising a receptacle for the flotation liquid, a source of supply of the charge to be separated, said source having a plurality of outlets, a corresponding number of carrier troughs arranged parallel to each other and spaced apart, a support for the carrier troughs, a track on which the support is adapted to reciprocate, said track being shaped to cause movement of the carrier troughs endwise into the liquid in the receptacle and then into co-action with said source of supply, means for reciprocating the carrier troughs upon said track, and means for causing automatic delivery of the charge from the source of supply into the carrier troughs; substantially as described.

45. 13. In apparatus for the separation of floatable minerals from materials with which they are associated, a wheeled carrier having suspended therefrom a series of troughs open at one end and spaced apart from each other, in combination with a subjacent receptacle for flotation liquid, a trackway upon which the carrier is movable and by which the carrier is caused to move into and out of the liquid in the receptacle, and means for feeding the materials into the carrier; substantially as described.

50. 14. In apparatus for the separation of floatable minerals from materials with which they are associated, a wheeled carrier having suspended therefrom a series of troughs open at one end and spaced apart from each other, in combination with a subjacent receptacle for flotation liquid, a trackway upon which the carrier is movable and by which the carrier is caused to move into and out of the liquid in the receptacle, and means for feeding the materials into the carrier; substantially as described.

55. 15. In apparatus for the separation of floatable minerals from materials with which they are associated, a wheeled carrier having suspended therefrom a series of troughs open at one end and spaced apart from each other, in combination with a subjacent receptacle for flotation liquid, a trackway upon which the carrier is movable and by which the carrier is caused to move into and out of the liquid in the receptacle, and means for feeding the materials into the carrier; substantially as described.

60. 16. In apparatus for the separation of floatable minerals from materials with which they are associated, a wheeled carrier having suspended therefrom a series of troughs open at one end and spaced apart from each other, in combination with a subjacent receptacle for flotation liquid, a trackway upon which the carrier is movable and by which the carrier is caused to move into and out of the liquid in the receptacle, and means for feeding the materials into the carrier; substantially as described.

65. 17. In apparatus for the separation of floatable minerals from materials with which they are associated, a wheeled carrier having suspended therefrom a series of troughs open at one end and spaced apart from each other, in combination with a subjacent receptacle for flotation liquid, a trackway upon which the carrier is movable and by which the carrier is caused to move into and out of the liquid in the receptacle, and means for feeding the materials into the carrier; substantially as described.

other in combination with a subjacent receptacle for flotation liquid, and a trackway inclined with respect to the horizontal and means for moving the carrier upon the 5 trackway to carry it into and out of the liquid in the receptacle; substantially as described.

In testimony whereof I affix my signature, in presence of two witnesses.
